RADIOGRAPHIC METHOD AND APPARATUS

Glenn W. Files, Oak Park, Ill., assignor to General Electric X-Ray Corporation, Chicago, Ill., a corporation of New York

Application March 10, 1938, Serial No. 195,183

18 Claims. (Cl. 250—62)

This invention relates to X-ray radiography, and more particularly to a method and apparatus for taking X-ray photographs.

Heretofore, in the X-ray radiographic art, "Bucky" diaphragms have been employed to reduce fogging of the film caused by secondary radiation emanating from the object being radiographed and from other objects in the path of the beam of X-rays. Such a diaphragm comprises alternate strips of X-ray impervious and X-ray pervious materials, the strips being disposed at an angle to one another, or radially toward a common axis or focusing point which is substantially the center of the anode or target of the X-ray tube. Such a diaphragm permits the primary X-ray radiation to pass therethrough and expose the sensitized radiographic plate while reducing the exposure of the plate to the secondary radiation. These diaphragms have not proved entirely satisfactory for all classes of radiography because the film or plate is frequently marked with a number of parallel, unexposed areas or lines produced by the radiographing of the X-ray impervious strips. It has heretofore been suggested that this defect could be overcome by bodily reciprocating the diaphragm during the exposure of the film or plate. However, the diaphragm must be stopped and restarted in the opposite direction at the end of each of its movements and therefore the X-rays are periodically cut off from the portions of radiographic plate lying beneath the opaque strips during this stopping and restarting of the diaphragm. This prevents the production of accurate, shadow-free radiographs.

X-ray radiographs of certain parts of the human body and certain objects cannot be made unless taken within a relatively short or very short period of exposure because an element of the part or object is in motion or because longer exposure detrimentally affects the part or object. In the case of such relatively short and very short exposures, the stopping and restarting of the diaphragm at the end of each reciprocation may require a large part of the total permissible exposure time and the consequent variation in the exposure density of the film or plate materially affects the clearness of the radiograph, making the same misleading and in many cases substantially useless.

It is accordingly an object of applicant's invention to provide a method and apparatus for making X-ray radiographs by means of Bucky diaphragms, by which these insufficiencies may be overcome and by which clear radiographs may

be produced by short and very short, as well as by relatively long periods of exposure.

A further object of applicant's invention is to provide an X-ray radiograph method and apparatus which shall result in the production of line-free, shadowless radiographs regardless of the time of exposure.

Applicant's invention further contemplates the provision of a method and apparatus in which, and by which, the diaphragm is moved in synchronism with the energization of the X-ray tube, such energization being determined by the frequency of the voltage impulses applied to the X-ray tube.

Another and more specific object of applicant's invention is to provide an X-ray radiographic method and apparatus in which, and by which, the diaphragm is vibrated, as distinguished from reciprocated, at a relatively high speed and in synchronism with the energization of the X-ray tube.

Other and further advantages of the invention will be apparent from the following description when taken in connection with the accompanying drawings wherein:

Fig. 1 is a view in perspective of one preferred means for operating the diaphragm in accordance with the invention.

Fig. 2 is a fragmentary, vertical section taken substantially along the line 2—2 of Fig. 1.

Fig. 3 is a fragmentary, vertical section taken along the line 3—3 of Fig. 1.

Fig. 4 is a diagrammatic view of a radiographic equipment including the diaphragm and operating means of Fig. 1.

Fig. 5 is a sketch illustrating the relation between the X-ray tube energizing impulses and the movements of the diaphragm.

Fig. 6 is a fragmentary plan view of a modified form of diaphragm operating means.

Fig. 7 is a further modified form of means for operating the diaphragm.

Fig. 8 is a perspective view of another form of diaphragm operating means.

Fig. 9 is a view in elevation of still another form of diaphragm operating means.

To illustrate the invention, there is shown on the drawings in Fig. 4 a radiographic equipment comprising an X-ray tube 10 from the anode of which emanates X-ray beams 12 which pass through the X-ray transparent plate 14 forming the object supporting surface of an X-ray table or stand.

The X-ray table or stand comprises a base plate or shelf 16 on which is movably supported in

spaced relation thereto, a Bucky diaphragm 18. A cassette 20 contains the radiographic plate or film and is adapted to be inserted between the diaphragm 18 and the base or shelf 16. The X-rays, after passage through the supporting surface 14 of the table, pass through the grid of the diaphragm 18 and impinge upon the radiographic plate or film within the cassette 20. The diaphragm cuts off the secondary radiation, as from the point 22 of the object illustrated diagrammatically at 24. However, if the diaphragm remains stationary during the exposure of the plate or film, the lines of the grid are photographed upon the plate and, if the diaphragm is reciprocated during exposure of the plate, shadow lines are developed thereon as an incident to the stopping and reversing of the diaphragm.

Applicant has discovered that if the diaphragm be shifted or vibrated through a relatively small range or distance of movement and in synchronism with the energization of the X-ray tube or the impulses of electric voltage applied thereto, these undesirable lines will be eliminated. This will be understood from the sketch of Fig. 5 wherein the numeral 26 indicates the full-wave rectified alternating voltage impressed on the X-ray tube. Below the voltage value represented by the intersection of the horizontal line 28 with the voltage wave 26, substantially no effective X-rays are produced by the X-ray tube 10. The voltage value represented by the line 28 is substantially one-half the peak value of the alternating voltage. Therefore, the time T_1 which is required for the voltage to build up to the value represented by the line 28 is substantially one-sixth of the total time of a half cycle of the alternating current. Similarly, the time T_1 required for the alternating current voltage to decrease from the value represented by the line 28 to zero is substantially one-sixth of the total time of a half cycle of the alternating current. The time— T_1 plus T —during which no effective X-rays are being projected upon the radiographic plate is therefore substantially one-third of the total time of a half cycle of the alternating current. In the case of sixty-cycle alternating current the total time of a half cycle of the alternating current is $\frac{1}{120}$ of a second, and the time— T_1 plus T —during which no exposure of the radiographic plate takes place is accordingly $\frac{1}{360}$ of a second.

According to applicant's method, the diaphragm is shifted or vibrated in synchronism with the impulse wave 26, the diaphragm being reversed in movement during the time— T_1 plus T —and moving at a substantially uniform speed during the time T_2 when the voltage value is sufficient to produce effective X-rays. Since no X-rays are being produced during the time that the diaphragm is stopping, reversing and starting up in the opposite direction, the radiographic plate will be entirely free from grid lines, as has been found by actual test. Since the diaphragm is synchronized in its movement with the energization of the X-ray tube, the exposures may be made in as short a time as desired without any danger of having the radiographic plate exposed to the X-rays during the reversing movements of the diaphragm. On the other hand, the exposure may be extended for any desired length of time, however long, without any danger of having the plate blurred by the frequent reversing of the diaphragm.

It will be seen, therefore, that applicant has

devised a method for taking X-ray radiographs by means of a diaphragm which consists in shifting or vibrating the diaphragm in synchronism with the energization of the X-ray tube, or the impulses of alternating current supplied to the tube, and in stopping, reversing and restarting the diaphragm during the time at which the value of the alternating voltage is below that required to produce X-rays effective in exposing the film.

One preferred form of apparatus by which the above described method may be performed is shown in Figs. 1 to 3. The diaphragm 14, as shown in these figures, may be of any desired construction comprising X-ray transparent plates 30 and 32 between which is mounted a grid structure 34 comprising alternate X-ray opaque and transparent strips 36 and 38, respectively. The plates 30 and 32 with the grid 34 interposed therebetween are mounted in a preferably rectangular frame 40 comprising bars or blocks 42 surrounding the grid 34 and clamping the strips thereof in proper position and a sheet metal shell 44 preferably of aluminum and of U-shaped cross section enclosing the blocks or bars 42. The diaphragm 14 is mounted on the base or shelf 16 by brackets 46 of such resilient material and so shaped as to permit the diaphragm to have the requisite degree of movement. The brackets are preferably of semi-soft rubber and each comprises a longitudinal portion 48 securely fastened to the frame 40 of the diaphragm as by bolts or the like 50. The bracket or support 46 is further provided with depending legs 52 extending between the diaphragm and the base or shelf 16 and is securely fastened to said base or shelf by bolts or the like 54 passing through inwardly turned feet 56. One of the brackets 46 is disposed at each corner of the diaphragm and the longitudinal axis of each bracket extends at right angles to the axis of movement or vibration of the diaphragm. Thus, while the diaphragm is substantially supported, the brackets 46 offer little, if any, interference to the movement of the diaphragm. The brackets 46 also prevent transmission of the vibrations of the diaphragm to the base or shelf 16 of the X-ray table.

In the form of the invention shown in Figs. 1 and 2, the diaphragm is operated in synchronism with the energization of the X-ray tube, or the impulses of alternating voltage applied to the tube, by a synchronous motor 58. This motor is mounted upon the base or shelf 16 of the X-ray table or stand and is of a size sufficient to fit within the space between the object supporting surface 14 and said base or shelf. The shaft 60 of the motor carries a gear 62 which meshes with a gear 64 carried by a stud or shaft 66 mounted on the frame of the motor 58. The gears 62 and 64 are preferably of fibre or other sound deadening material.

Where the alternating current supplied is of 60-cycle frequency and the motor 58 is a synchronous motor operating at 1800 R. P. M., the ratio between the gears 62 and 64 is two to one in order that the gear 64 may have a speed of 3600 R. P. M. Of course synchronous motors of other speeds may be employed and the ratio between the gears 62 and 64 varies correspondingly to obtain this desired speed of rotation for the gear 64. The gear 64 is connected to the diaphragm 14 by a link 68 pivoted eccentrically to the gear 64 and to a cross head 70 bolted to one side of the frame 40 centrally thereof. The

distance between the axis of rotation of the gear 64 and the eccentric pin 72, which pivotally connects the link 68 thereto, is one-half the desired distance of movement or vibration of the diaphragm 14. A distance of movement or vibration of the diaphragm 14 equal to one millimeter has been found preferable, and accordingly the eccentric pin 72 is located on the gear 64 at a distance equal to one-half a millimeter from the axis of rotation of said gear. Suitable conventional means may be provided, if necessary or desirable, to maintain the motor 58 in synchronism with the supply voltage.

In the form of the invention shown in Fig. 6, the shaft 60 of the synchronous motor has secured thereto a cam 74 engaging a pair of cam rollers or followers 76 journaled on pins 78 carried by a plate 80 bolted to one side of the frame 40 and centrally thereof. If the speed of rotation of the shaft 60 is 1800 R. P. M., the cam 74 will be provided with alternate quadrants 82 and 84 having cam surfaces of progressively increasing radii in the direction of rotation and alternate quadrants 86 and 88 of progressively decreasing radii in the direction of rotation. The cam followers 76 may be maintained in constant engagement with the surface of the cam 74 by the natural resiliency of the rubber mountings or brackets 46. Additional resilient means for maintaining the cam followers or rollers 76 in engagement with the cam 74 may be provided if desired. This means may comprise a pair of coil springs 90 interposed between the opposite side of the frame 40 and a flange 92 or bar 92 secured to, or formed integrally with, the base or shelf 16 of the X-ray stand or table.

In this form of the invention the cam 74 constitutes a means for controlling the movements of the diaphragm and for moving the diaphragm in one direction, and the rubber mountings or brackets 46 or the springs 90 or both brackets and springs constitute a means for maintaining the cam followers 76 in engagement with the cam and a means for moving the diaphragm in the opposite direction.

Where the motor shaft 60 rotates at a speed other than 1800 R. P. M., the cam surface of the cam 74 will be suitably modified to cause the diaphragm 14 to complete its cycle of movement in $\frac{1}{60}$ of a second and in synchronism with the alternating current supply voltage. By providing a single small cam roller and providing a cam whose surface has small but sudden drops or depressions between the portions 82 and 86 and the portions 84 and 88, and a sudden rise or elevation between the portions 88 and 82 and between the portions 86 and 84, the time required to effect a stopping, reversing and restarting of the diaphragm at the end of each half cycle of its movement may be as small as desired. However, a cam having a smoothly varying cam surface, as disclosed in Fig. 6, will accomplish the stopping, reversing and restarting of the diaphragm well within the allotted time of $\frac{1}{360}$ of a second.

In the form of the invention shown in Fig. 7, the motor shaft 60 has secured thereto, and eccentrically with respect to its axis, an eccentric disk 94. The disk 94 drives or vibrates the diaphragm 14 by means of an eccentric strap 96 having an integral arm 98 pivotally connected as at 100 to the cross head 70 secured to the frame 40 of the diaphragm. This form of the invention has an operating advantage over the

form of the invention shown in Fig. 1 in respect to the quietness of operation but requires that the motor shaft 60 have a speed of rotation of 3600 R. P. M.

In the form of the invention shown in Fig. 8, the diaphragm 14 is driven by a spring 102 or other vibratory means having a natural period of vibration equal to the cycle frequency of the alternating current supply voltage. The spring 102 may be connected to the frame 40 of the diaphragm in any desired manner and interposed between the diaphragm and an upstanding lug 104 secured to, or formed integrally with, the base or shelf 16 of the X-ray table or stand. A solenoid 106 having an armature 108 secured to one side of the frame 40 is provided to initiate the vibration of the diaphragm. The energizing circuit for this solenoid may be interlocked in any desire and conventional manner (not shown) with the X-ray tube energizing circuit to that upon closure of the energizing circuit the vibration of the diaphragm will be initiated, it being understood that the solenoid 106 is only momentarily energized upon the energization of the X-ray tube.

In order to maintain the vibrations of the spring 102 or other vibratory means in synchronism with the alternating current supply voltage over an extended period of exposure, synchronous switch means of conventional structure may be provided to periodically retension the spring 102 or other vibratory means.

In the form of the invention shown in Fig. 9, a small motor 110 is mounted upon a bracket 112 secured to, and extending laterally from, one side of the diaphragm frame 40. In this form of the invention, reliance is had upon the inherent vibration of the motor 110 to effect a vibration of the diaphragm 14. Adjustable-phase control means such as an adjustable capacity 114 and an adjustable inductance 116 may be provided for the purpose of maintaining the inherent vibrations of the motor in synchronism with the alternating current supply voltage.

It will be seen from the above description that applicant has provided a method and means for making line-free, shadowless and unblurred X-ray radiographs by means of diaphragms regardless of the time of exposure.

Changes may be made in the form, construction and arrangement of the parts without departing from the spirit of the invention or sacrificing any of its attendant advantages, and the right is hereby reserved to make all such changes as fairly fall within the scope of the following claims.

The invention is hereby claimed as follows:

1. A method of making short exposure X-ray radiographs which comprises energizing an X-ray tube by pulsating current and vibrating a diaphragm of alternate X-ray opaque and X-ray transparent strips transversely of the produced beam of X-rays in synchronism with the pulsating current, the reversal of the diaphragm at each of its limits of movement being accomplished within the time interval that the magnitude of the pulsating current impulse is below the value required to produce X-rays.

2. A method of making short exposure X-ray radiographs which comprises energizing an X-ray tube with pulsating, full-wave, rectified impulses of alternating current, vibrating a diaphragm of alternate X-ray opaque and X-ray transparent strips across the beam of X-rays in synchronism with the energizing impulses, the

- reversal of the diaphragm at the limit of its movement being accomplished in the time interval that successive impulses of the energizing current are below the value required to produce X-rays.
3. In an X-ray radiographic apparatus for short exposures, an X-ray tube, means for energizing said tube with pulsating current, a diaphragm comprising alternate X-ray opaque and X-ray transparent strips and means for cyclically shifting said diaphragm in synchronism with the pulsating current and reversing the movement of the diaphragm in the time interval that the pulsating current is below the value required to produce X-rays.
4. In an X-ray radiographic apparatus for short exposures, an X-ray tube, means for energizing said tube with pulsating current, a sensitized film, a support, a diaphragm comprising alternate X-ray opaque and X-ray transparent strips interposed between said X-ray tube and said film, flexible supporting means for mounting the diaphragm on said support, means for vibrating said diaphragm in synchronism with the pulsating current comprising a synchronous motor adapted to be energized from said source of pulsating current, a shaft driven by said motor, a bracket secured to said diaphragm and a link pivotally connected to said bracket and to said shaft eccentrically with respect to the axis of rotation of said shaft.
5. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for connecting the shaft of the motor to said diaphragm.
6. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising a synchronous motor adapted to be energized from said source of pulsating current, a shaft driven by said motor, a bracket secured to said diaphragm and a link pivotally connected to said bracket and to said shaft eccentrically with respect to the axis of rotation of said shaft.
7. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current comprising a synchronous motor adapted to be energized from said source of pulsating current, a disk eccentrically mounted on the motor shaft and an eccentric strap pivotally connected to the frame of the diaphragm and enclosing said disk.
8. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising a synchronous motor adapted to be energized from said source of pulsating current, a disk eccentrically mounted on the motor shaft and an eccentric strap pivotally connected to the frame of the diaphragm and enclosing said disk.
9. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising a synchronous motor adapted to be energized from said source of pulsating current and mounted on said support, a cam driven by the motor shaft, a cam follower secured to the diaphragm, and resilient means for maintaining said follower in engagement with said cam.
10. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising a synchronous motor adapted to be energized from said source of pulsating current and mounted on said support, a cam driven by the motor shaft, a cam follower secured to the diaphragm, and resilient means for maintaining said follower in engagement with said cam.
11. In an X-ray radiographic apparatus for short exposures, an X-ray tube, means for energizing said tube with pulsating current, a sensitized film, a diaphragm comprising alternate X-ray opaque and X-ray transparent strips interposed between said X-ray tube and said film, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising a synchronous motor adapted to be energized from said source of pulsating current and mounted on said support, a cam driven by the motor shaft, a cam follower secured to the diaphragm, and resilient means for maintaining said follower in engagement with said cam.

ing the diaphragm in synchronism with the pulsating current comprising resilient means having a natural period of vibration conforming to the frequency of the pulsating current.

5 12. In an X-ray radiographic apparatus for short exposures, an X-ray tube, means for energizing said tube with pulsating current, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means for vibrating the diaphragm in synchronism with the pulsating current comprising resilient means having a natural period of vibration conforming to the frequency of the pulsating current, and means for initiating the movement of the diaphragm.

15 13. In an X-ray radiographic apparatus for short exposures, an X-ray tube, means for energizing said tube with pulsating current, a sensitized film, a support, a diaphragm comprising alternate X-ray opaque and X-ray transparent strips interposed between said X-ray tube and said film, flexible supporting means for mounting the diaphragm on said support, resilient means having a natural period of vibration conforming to the frequency of the pulsating current for vibrating said diaphragm in synchronism with said pulsating current and reversing the movement of the diaphragm in the time interval that the pulsating current is below the value required to produce X-rays, and means comprising a solenoid adapted to be connected to the source of pulsating current for initiating the movement of the diaphragm upon energization of the X-ray tube.

20 14. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, resilient means having a natural period of vibration conforming to the frequency of the pulsating current for vibrating said diaphragm in synchronism with said pulsating current and reversing the movement of the diaphragm in the time interval that the pulsating current is below the value required to produce X-rays, means comprising a solenoid adapted to be connected to the source of pulsating current and intermittently energized thereby for initiating the movement of the diaphragm upon energization of the X-ray tube, and for retensioning said resilient means whereby to maintain the movements of the diaphragm in synchronism with the pulsating current.

25 15. In an X-ray radiographic apparatus for short exposures, an X-ray tube, means for energizing said tube with pulsating current, a sensi-

tized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means comprising electric motor means having a period of mechanical vibration conforming to the frequency of the pulsating current, and means for mounting said electric motor means on said diaphragm.

30 16. In an X-ray radiographic apparatus for short exposures, an X-ray tube, a source of pulsating current, means for energizing said tube from said source, a sensitized film, a support, a diaphragm comprising alternate X-ray opaque and X-ray transparent strips interposed between said X-ray tube and said film, flexible supporting means for mounting the diaphragm on said support, and means for vibrating said diaphragm in synchronism with the pulsating current and reversing the movement of the diaphragm in the time interval that the pulsating current is below the value required to produce X-rays, said means comprising electric motor means adapted to be energized from the source of pulsating current and having a period of mechanical vibration conforming to the frequency of the pulsating current, means for mounting said electric motor means on said diaphragm whereby said diaphragm is vibrated in synchronism with the pulsating current, and phase control means for maintaining the vibrations of the motor in synchronism with the pulsating current.

35 17. In X-ray radiographic apparatus, a shiftable diaphragm having a frame and a grid, said grid comprising alternate X-ray opaque and X-ray transparent strips, a support for said diaphragm and a plurality of spaced, flexible brackets secured to said frame and to said support for permitting substantially free shifting of said diaphragm at right angles to the grid strips while preventing movement of the same in a direction longitudinally of the grid strips.

40 18. A method of making short exposure X-ray radiographs which comprises energizing an X-ray tube by current pulsating in magnitude at a substantially constant frequency from a value below that required to produce effective X-rays to a value sufficient to produce effective X-rays, and shifting a diaphragm of alternate X-ray opaque and X-ray transparent strips back and forth across the beam of X-rays and between the X-ray tube and a radiographic film at a speed such that a complete movement in one direction is wholly accomplished during the time that the magnitude of the energizing impulse is sufficient to produce effective X-rays and the direction of movement of the diaphragm is reversed during the time interval when the magnitude of the energizing impulse is below the value required to produce effective X-rays.
